CLAIM

The ornamental design for a measuring tape case, as shown and described.

DESCRIPTION

FIG. 1 is a top, front and right side perspective view of a measuring tape case showing my new design;

FIG. 2 is a top plan view;

FIG. 3 is a left side elevational view;

FIG. 4 is a bottom plan view;

FIG. 5 is a front elevational view;

FIG. 6 is a rear elevational view; and

FIG. 7 is a sectional view thereof, taken along the line A—A of FIG. 2.
